CLAIM

The ornamental design for a sandwich gripper, as shown and described.

DESCRIPTION

FIG. 1 is a bottom, front, right side perspective view of a first embodiment of a sandwich gripper showing my new design in an open configuration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another bottom, front, right side perspective view thereof, shown in an environment of use;

FIG. 9 is another bottom, front, right side perspective view thereof, shown in a closed configuration;

FIG. 10 is a bottom, front, right side perspective view of a second embodiment of a sandwich gripper showing my new design in an open configuration;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof; and,

FIG. 17 is another bottom, front, right side perspective view thereof, shown in an environment of use.

The broken lines shown in FIGS. 1-5 and 10-14 illustrate portions of the sandwich gripper that form no part of the claimed design. The broken lines illustrating the sandwich in FIGS. 8 and 17 are environment, that form no part of the claimed design.

1 Claim, 8 Drawing Sheets
